UNITED STATES PATENT OFFICE

PETER K. KARBERG, OF DUBUQUE, IOWA, ASSIGNOR TO H. B. GLOVER COMPANY, OF DUBUQUE, IOWA, A CORPORATION OF IOWA

GARMENT

Application filed April 27, 1929. Serial No. 358,475.

My invention relates to under garments or garments of like character such as drawers, union suits, pajamas, shorts, trunks, track or running pants and similar articles of apparel and contemplates generally improved 5 waist constructions therefor.

The invention has for its principal object the provision of elastic pieces in the waistband of an article of the character described and the sewing of the body of the garment thereto in such a way that the cloth attached thereto will fold and unfold uniformly with the contraction and extension of the elastic pieces, thus making for 10 compact and neatness in appearance, as well as serviceability.

Other objects and advantages will be evident from the following description and the accompanying drawings in which—

20 Figure 1 is a view showing the invention as applied to drawers or pants of the usual type;

Fig. 2 shows the invention as applied to union suits;

25 Fig. 3 is a view of the waistband showing the manner in which the elastic pieces are attached thereto; and

Fig. 4 is a view showing the manner in which the waistband is attached to the body 30 of the garment.

While the invention is applicable to all types of underwear, pajamas, shorts, trunks and the like, two types have been shown in Figs. 1 and 2. Referring to Fig. 1 the usual 35 type of drawers or pants is shown having a body composed of members 6 and 7 joined by a seam 8 to form legs 9 and 10 and a waist portion 11. The waist may have the elastics built therein in various ways, that is, with 40 or without a separate waistband. A waistband 12, shown in detail in Fig. 3, is in this particular case attached to the garment at the waist. This band consists of inelastic back and front portions 13 and 16, 17, with 45 elastic web pieces 14, 15, disposed between and fastened at their ends to said back and front portions. This waistband is superimposed upon the outside of the body portion, at the waistline and sewed thereto by its 50 edges. In order to prevent raveling of the

edges the cloth portions of the waistband are cut wider than the elastic members, as indicated at 18, to permit the edges to be folded under. The same precaution is taken, naturally, in sewing the ends of the portions 55 13, 16, and 17 to the ends of the elastics, and that gives the further advantage of greater strength and durability and avoids any danger of tearing of the material at the stitches joining the elastics to the material, under the 60 pull of the elastics.

The band which is shorter than the waist of the garment is attached thereto by sewing the cloth portions thereof smoothly over the waist portion of the garment as indicated, the 65 excess material of the waist being gathered beneath the elastic members of the waistband. This excess material is sewed to the elastic members in their extended condition, the same being sufficiently extended to permit 70 this material to be sewed smoothly thereon. More particularly, in attaching the waistband the sewing operation is as follows: A front portion, such as 16, is sewed to the waist by two rows of stitches 19 and 20. When the 75 elastic 14 is reached it will be stretched by the operator approximately to a predetermined extent and sewed in that condition to the waist by continuing the lines of stitches 19 and 20. It will be seen that when the elastic 80 14 is permitted to contract the cloth of the body of the garment will be drawn up in a uniformly pleated or tucked fashion, as shown at 21. The back portion 13 will then be sewed by continuing the same lines of 85 stitching; and the elastic 15 will be stretched and sewed in the same manner as the elastic 14, the stitching continuing along the front portion 17, as will be obvious.

Referring to Fig. 2 which shows the invention as applied to a union suit the same principles are involved as have been set forth, the front portions indicated by the same numerals 16 and 17 are connected by elastic pieces under which the excess material 95 at the waistband of the garment is gathered uniformly so as to permit stretching and contraction of the elastic pieces.

My improved construction offers a number of decided advantages. Because of the 100

improved construction a number of economies in manufacture are possible. The waistband may be made up separately, as indicated in Fig. 3, and then in a single operation sewed to the garment. Because of the manner in which the elastic pieces are attached, the material in the body portion of the garment, lying under these elastics, need not be removed to permit stretching of said elastics. 5 This manner of attaching the waistband also permits the ends of the elastic pieces 14 and 15 to be interposed between the portions 13, 16, and 17 of the waistband and the cloth of the body of the garment, thereby effectively concealing these ends and preventing ridges or bunches from being formed. Furthermore, in the construction here provided the elastic pieces are shielded from contact with the body by the intervening material of the 10 waist portion. When the elastic pieces are stretched this gathered material unfolds to permit the elongation so that the elastic itself is not caused to slide over or to pinch or irritate the body. 15 Referring particularly to the type of garment shown in Fig. 2 it will be seen that the waistband may be attached directly over the customary union suit. The elastic waistband serves to support the lower part of the 20 garment about the hips whereby a certain amount of material is loosely provided above the waist. In this manner the garment, instead of hanging completely from the shoulders, is partially supported at the waist-line and movements of the arms and shoulders requiring the garment to be lifted upon the body need only lift that portion of the garment lying between the shoulder and the 25 waist line, instead of the garment therebelow as well, since the belt holding the trousers usually causes this movement of the garment to be difficult. 30

While I have thus described and illustrated this specific embodiment of my invention 45 I am aware that numerous changes and alterations may be made therein without materially departing from the spirit and scope of the invention and I do not wish to be limited except as required by the prior art.

50 I claim:

1. In an article of the character described having a waist portion of inelastic fabric, a waistband for said waist portion comprising inelastic fabric back and front portions, and elastic web members superimposed on the outside of the waist portion between said back and front portions arranged to lie at the sides of the waist portion, the normal length of said waistband being less than the corresponding length of the waist portion, the excess of fabric in the waist portion being gathered between the ends of each of said elastic members, longitudinal stitches smoothly connecting the elastic members and the fabric of the waist portion when the former

are in their stretched condition, the fabric being drawn up thereby in a gathered manner when the elastic members are in their normal condition, whereby the fabric is caused to fold and unfold with contraction 70 and extension of the elastic members.

2. In a garment having leg portions, a waist construction for said garment comprising inelastic waist material reaching completely around the waistline having gathers 75 in said material at opposite sides of the waist, and elastic web members disposed at opposite sides of the waist spanning the outside of the gathers and having the raw ends thereof tucked under the adjacent material 80 of the waist and sewed in place, the said elastics having the gathers stitched thereto so as to fold and unfold uniformly in the contraction and stretching of the elastics.

3. In a garment having leg portions, a 85 waist construction for said garment comprising inelastic waist material extending completely around the waistline, front and back portions of inelastic material superimposed upon the waist material so as to make the 90 front and back portions of plural plies, the front and back portions defining gaps therebetween at opposite sides of the waist, the waist material being collected in gathers in said gaps, and elastic web members disposed 95 in said gaps spanning the gathered waist material and having the raw ends thereof tucked between the plies of the front and back portions of the waist and sewed in place, the said elastics having the gathers stitched thereto 100 so as to fold and unfold uniformly in the contraction and stretching of the elastics.

4. In a garment having leg portions, a waist construction for said garment comprising inelastic waist material extending completely around the waistline, and a waistband assembly comprising inelastic front and back portions, and a pair of elastic web members for the opposite sides of the waistband sewed at their ends to the adjacent ends 105 of the front and back portions to complete the waistband assembly, said waistband assembly being superimposed upon the waist material, with the ends of the elastics concealed beneath the ends of the inelastic portions, by stitching lengthwise of the edges of the front and back portions whereby to make the front and back portions of the waist two-ply, and stitching lengthwise of the elastic web members, while the latter are stretched, 110 whereby to fasten the same to the waist material so that the waist material is disposed in gathers at opposite sides of the waist when the elastic web members contract to normal condition, the said gathered material being 115 thereby arranged to fold and unfold uniformly with the contraction and stretching of the elastic members.

5. In a garment having leg portions, a waist construction for said garment compris- 120

ing inelastic waist material extending completely around the waist line, elastic web members disposed at opposite sides of the waist spanning the outside of gathers of 5 waist material, the said web members being sewed longitudinally to the waist material so that the gathers are arranged to fold and unfold uniformly in the contraction and stretching of said web members, and an outer 10 ply of inelastic material sewed to the waist material at the front and back of the waist and reaching over the elastic web members at the sides of the waist and sewed thereto also.

15 In witness of the foregoing I affix my signature.

PETER K. KARBERG.
